[57] CLAIM

The ornamental design for a wall clock, as shown and described.

DESCRIPTION

FIG. 1 is a front elevational view of a wall clock showing my new design, the rear being flat, plain, and unornamented;

FIG. 2 is a bottom plan view thereof;

FIG. 3 is a top plan view thereof;

FIG. 4 is a left side elevational view thereof;

FIG. 5 is a right side elevational view thereof; and,

FIG. 6 is a front elevational view of a second embodiment of my new design for FIGS. 1-5 wherein the sole difference is the addition of the grillwork.

FIG. 1

FIG. 2

FIG. 3
